CLAIM

We claim the ornamental design for a dosing spoon and holding clip assembly, as shown and described.

DESCRIPTION

FIG. 1 depicts a perspective view of a dosing spoon and holding clip assembly in condition of use with unclaimed environmental structure.

FIG. 2 is a front elevation view thereof.

FIG. 3 is a rear elevation view thereof.

FIG. 4 is a side elevation view of thereof.

FIG. 5 is an opposite side elevation view thereof.

FIG. 6 is a top plan view of thereof.

FIG. 7 is a bottom plan view thereof.

FIG. 8 depicts a perspective view of a dosing spoon and holding clip assembly.

FIG. 9 is a top plan view thereof.

FIG. 10 is a bottom plan view thereof.

FIG. 11 is a front elevation view thereof.

FIG. 12 is a rear elevation view thereof.

FIG. 13 is a side elevation view thereof; and,

FIG. 14 is an opposite side elevation view thereof.

The broken lines in the drawings illustrate environmental structure on the article and form no part of the claimed design.
